CLAIM

The ornamental design for a film-transferring device, as shown and described.

DESCRIPTION

FIG. 1 is a top plan view showing my new design for a film-transferring device;

FIG. 2 is a front elevational view thereof;

FIG. 3 is a left side elevational view thereof;

FIG. 4 is a rear elevational view thereof;

FIG. 5 is a bottom plan view thereof;

FIG. 6 is a right side elevational view thereof;

FIG. 7 is a perspective view thereof, as viewed from the left;

FIG. 8 is a cross-sectional view thereof taken along line 8—8 indicated in FIG. 6, the “J” shaped portion indicated by the left-side-up hatching at the left end of the article and the “U”-shaped portion indicated by the right-side-up hatching and the left-side-up hatching along the right side circumference of the article being transparent;

FIG. 9 is a cross-sectional view thereof taken along line 9—9 indicated in FIG. 2. The left side up hatching on the left side indicates transparency;

FIG. 10 is a cross-sectional view thereof taken along line 10—10 indicated in FIG. 2; The left side up hatching on the right side indicates transparency; and,

FIG. 11 is a reference view thereof showing state of use.
